ELECTRIC TEA KETTLE

Victor L. Fairthorne, Willowdale, Ontario, Canada,
assignor to Westinghouse Canada Limited

Filed Mar. 4, 1974, Ser. No. 447,757

Claims priority, application Canada Oct. 29, 1973

Term of patent 7 years

Int. Cl. D7—02

U.S. Cl. D7—62

FIG. 1 is a perspective view of the top and side of an electric tea kettle showing my new design.

FIG. 2 is a perspective view of the bottom and side thereof.

FIG. 3 is an elevational view of the front thereof.

I claim:

The ornamental design for an electric tea kettle, as shown.
